UNITED STATES PATENT OFFICE.

JAMES F. DOBBINS, OF BROOKLYN, NEW YORK.

VERNIER DIAL.

Application filed October 20, 1925. Serial No. 63,584.

To all whom it may concern:

Be it known that I, JAMES F. DOBBINS, a citizen of the United States of America, residing at Brooklyn, in the county of Kings 5 and State of New York, have invented certain new and useful Improvements in Vernier Dials, of which the following is a specification.

This invention relates to an improved adjusting means for radio dials, such as are used on radio receiving sets to adjust the variable condenser, variometer, coupler, etc. In most cases the adjustment is effected by turning the dial directly with the hand, but 15 it is often extremely difficult to obtain accurate "tuning" by this method, as the dials are generally made with a fair amount of friction, so that when sufficient pressure is applied to overcome the friction, the dial 20 moves farther than anticipated.

I am aware that reduction gears of various forms have been proposed to overcome this difficulty, but, with such gear, it is usually impossible to get a quick adjustment of the 25 dial through a large angle, which is often desirable.

One purpose of my invention is to devise a radio dial in which the fine adjustment may be made accurately and the coarse adjustment quickly, all through the same handle or finger piece.

Another object of the invention is to simplify devices of this character so that the same may be made cheaply and without 35 special gear cutting machinery.

From the description of the principle of my invention which follows, it will be apparent that it has other applications than to radio dials, being adapted to the adjustment of any spindle where both accurate and wide range of adjustment is required.

Referring to the drawings in which what I now consider a preferred form of my invention is shown—

Fig. 1 is a plan view of a radio dial constructed according to my invention.

Fig. 2 is a side elevation of the same.

Fig. 3 is a vertical section on line 3—3 of Fig. 1.

Fig. 4 is a detail, and

Fig. 5 is a front view of the adjusting pinion.

The dial proper 1 may be provided with the usual graduations 2 denoting wave lengths. It is shown as provided with a central boss 3; having a downwardly facing

bore 4 in which is secured a metallic sleeve 5 for mounting it on a spindle (not shown). A set screw 6 may be used to clamp it to the spindle. Around the edge of the dial 60 or disc 1, I provide bevel gear teeth 6'. Said teeth need not be accurately cut but may be in the form of radial knurling or raised graduations on the beveled outer edge 7 of the disc or any form of surface which 65 will prevent slippage.

Journaled on the sleeve 5 is an arm 8 having an upwardly extending outer end 9 on which is rotatably mounted, as by means of pin 10, a bevel pinion 11. The lower end 70 of sleeve 5 may be burred over to hold the arm 8 thereon. Said pinion meshes with the teeth 6 on disc 1 and like it is provided with teeth 12 which may be in the 75 form of knurling on the same pitch as the teeth 6', or other form of surface to prevent slippage between the gears.

The face of the pinion 11 is also provided with "vernier" graduations 13 which are designed to read to the units or decimals of 80 the numbers on the main dial. By this means the fine graduations on the main dial may be omitted, the operation depending on the graduations on the smaller gear for this 85 purpose.

From the foregoing the operation of my invention will be readily apparent. All adjustments of the dial are secured by grasping the pinion 11 with the fingers, the teeth on the same giving one a good purchase. If 90 a large movement is desired, the operator swings the arm 8 bodily around on sleeve 5 carrying the dial with it by preventing the pinion from turning on its own axis as he revolves it with the arm. On the other 95 hand, when fine adjustment is desired, the operator turns the pinion on its own axis so as to revolve the dial slowly and with extreme precision. The bevel pinion forms an ideal operating handle for the purpose 100 as it is located above and near the edge of the main dial. If desired, the bent up portion 9 on which the pinion is journaled may be made heavier as by providing additional weight at that point, so that said arm 8 will 105 also hang vertically downward from pivot 5 like a pendulum.

In accordance with the provisions of the patent statutes, I have herein described the principle and operation of my invention, together with the apparatus which I now consider to represent the best embodiment there- 110

of, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. An adjusting means for radio dials and the like comprising the combination with the dial mounted for rotation about an axis, of an arm swiveled on said axis, and a bevel gear rotatably mounted on said arm and contacting with the top of said dial.
2. An adjusting means for radio dials and the like comprising the combination with the dial mounted for rotation about an axis and having bevel teeth on the top thereof, of an arm swiveled on said axis, and a bevel gear rotatably mounted on said arm and meshing with the teeth on said dial.
3. An adjusting means for radio dials and the like comprising the combination with the graduated dial mounted for rotation about an axis, of an arm swiveled on said axis, and a bevel gear rotatably mounted on said arm and contacting with the top of said dial,

said bevel gear being provided with graduations of lesser value than the graduations on said dial.

4. An adjusting means for radio dials and the like comprising the combination with the graduated dial mounted for rotation about an axis and having bevel teeth on the top thereof, of an arm swiveled on said axis, and a bevel gear rotatably mounted on said arm and meshing with the teeth on said dial, said bevel gear being provided with graduations of lesser value than the graduations on said dial.

5. An adjusting means for radio dials and the like comprising the combination with the dial mounted for rotation about an axis, of an arm swiveled on said axis, and a gear rotatably mounted on said arm and connecting with said dial, said gear being so located that it may serve as the finger piece.

6. An adjusting means for radio dials and the like comprising the combination with the dial mounted for rotation about an axis, of an arm swiveled on said axis, said arm being made heavier adjacent its outer end, and a gear rotatably mounted on said arm and connecting with said dial, said gear being so located that it may serve as the finger piece.

In testimony whereof I have affixed my signature.

JAMES F. DOBBINS.
